REFRIGERATION

Alvar Lenning, Stockholm, Sweden, assignor, by
mesne assignments, to Servel, Inc., New York,
N. Y., a corporation of Delaware

Application August 17, 1937, Serial No. 159,450
In Germany September 3, 1936

9 Claims. (Cl. 62—119.5)

My invention relates to refrigeration, and more particularly to absorption refrigeration apparatus employing an auxiliary pressure equalizing gas.

It is an object of my invention to provide an improvement in refrigeration apparatus to increase the surface contact effected between a gas and a liquid. I accomplish this by providing barriers at spaced intervals in a conduit to form pools in the path of flow of liquid, inserting in the conduit one or more members to provide dams at spaced intervals between the barriers, and permitting the flow of liquid through a lower part of each dam. By providing dams of this character in the path of flow of liquid between the barriers, not only is the liquid surface increased, but a film which forms on the surface of the liquid is effectively broken up when liquid flows from one pool to the successive pool due to the eddy effect produced by flow of liquid underneath the dams.

I preferably employ a helical member within a conduit to provide dams which permit the flow of liquid through a lower part of each dam. In addition to providing fresh liquid surfaces, a helical member possesses the additional advantage that a whirling motion is imparted to the gas to improve further the surface contact between the gas and liquid.

The invention, together with the above and other objects and advantages thereof, will be better understood from the following description and accompanying drawings forming a part of this specification, and of which Fig. 1 diagrammatically illustrates an absorption refrigeration apparatus embodying my invention; Fig. 2 is an enlarged fragmentary sectional view of a part of the cooling element and absorber shown in Fig. 1 to illustrate more clearly one embodiment of my invention; and Figs. 3 and 4 are sectional views similar to Fig. 2 illustrating modifications of the invention.

Referring to Fig. 1, I have shown my invention in connection with absorption refrigeration apparatus of a uniform pressure type in which an auxiliary pressure equalizing gas is employed. Apparatus of this type is well known and includes a cooling element or evaporator 10 disposed in an enclosed space 11 which may form a food storage compartment of a thermally insulated cabinet 12. Refrigerant fluid, such as ammonia, passes through a conduit 14 into the cooling element 10 and evaporates and diffuses therein into an inert gas, such as hydrogen, to produce a refrigerating effect. The resulting gas mixture of refrigerant and inert gas flows from cooling element 10

5 through a conduit 15, gas heat exchanger 16, and a vertically extending conduit 17 which is connected at its lower end with the lower end of an absorber 18 provided with a plurality of cooling fins 19. In absorber 18 refrigerant vapor is absorbed into solution by a suitable liquid absorbent, such as water, which enters through a conduit 20. The inert gas, which is practically insoluble and weak in refrigerant, is returned to the upper part of cooling element 10 through a conduit 21, gas heat exchanger 16, and a conduit 22; and the absorption liquid flowing downward through the absorber 18 in counter-flow to the gas mixture becomes enriched in refrigerant and passes 10 through the lower end of conduit 17 into an accumulation vessel 23. From the accumulation vessel 23 enriched absorption liquid is conducted through a liquid heat exchanger 24 to a coil 25 which is disposed about a flue 26 which extends 15 vertically upward through a generator 27.

20 By heating generator 27, as by a gas burner 28, for example, refrigerant vapor and absorption liquid are raised by vapor lift action through conduit 29 from coil 25 to the upper part of generator 27. Liberated refrigerant vapor entering generator 27 through conduit 29, as well as refrigerant vapor expelled from solution in the generator, flows upward into an air-cooled condenser 30. Refrigerant vapor is liquefied in condenser 30 25 and returned to cooling element 10 through conduit 14 to complete the refrigerating cycle. The weakened absorption liquid from which refrigerant has been expelled is conducted from generator 27 through conduit 31, liquid heat exchanger 24, and conduit 20 into the upper part of absorber 18.

30 A vessel 32 is connected by a conduit 33 to the lower part of condenser 30 and by conduit 34 to the gas circuit, as at the conduit 17, for example, so that any inert gas which may pass into the condenser can flow into the gas circuit. Refrigerant vapor not liquefied in condenser 30 flows through conduit 33 to displace inert gas in vessel 32 and force such gas through conduit 34 into the gas circuit, so that the total pressure in the system is raised and an adequate condensing pressure is obtained to insure condensation of refrigerant vapor in condenser 30.

35 The absorber 18 is of the coil type and includes a plurality of inclined conduits 35 which are connected to each other and arranged in the same vertical plane. Referring to Fig. 2, the lower parts of conduit 35 are indented at spaced intervals at 36 to provide barriers over which liquid must flow. Within each conduit 35 is arranged

a helical member or coil 37 having the lower parts of successive turns disposed between the indentations 36. The helical member 36 is arranged within conduit 35 in such a manner that the member irregularly contacts the inner wall of the conduit to provide spaces 39 between the member and inner wall of the conduit.

By providing the indentations 36 and helical member 37, the normal downward flow of liquid in conduits 35 is retarded by the indentations 36. The liquid passes over the barriers formed by the indentations 36, and the flow of liquid is subsequently checked by the dams 38 formed by the lower parts of helical member 37. Liquid flows underneath the dams due to the narrow gaps 39 between the lower parts of helical member 37 and the inner wall of conduit 34 whereby the flow of liquid is throttled. The throttling of liquid flow produces an eddy effect and changes the rate of flow of liquid. With flow of liquid taking place in conduit 35 in the manner just described, the gas and liquid surface contact is improved considerably because of the destruction of a film which forms on the surface of the liquid. This film is due to the absorption of refrigerant gas at the surface of the liquid, and it is a distinct advantage to break up this surface film containing a relatively high amount of refrigerant so that fresh gas and liquid contact surfaces are provided.

The film which forms at the surface of the liquid contacts the helical member 37 at the dams 38 and, due to the manner of liquid flow, is drawn downward into the liquid at the dams so that it is broken up and a more uniform absorption solution is produced. The breaking up of the surface film is also aided by the fact that the current of liquid is divided into a number of partial currents when passing underneath the dams 38 due to the irregular contact effected between the helical member 37 and inner wall of the conduit 35. The helical member 37 also imparts a whirling motion to the gas flowing through the conduit to further improve the contact between the gas and liquid.

In Fig. 3 I have shown a modification of the invention in which a helical band or strip 40 is arranged within conduit 35 instead of a helical wire. The strip 40 is disposed within conduit 35 in such a manner that one longitudinal edge thereof bears against the inner wall of the conduit. In this longitudinal edge are formed notches or recesses 41 through which liquid must pass. The flow of liquid is accelerated at the recesses 40 to produce an eddy effect whereby the surface film is effectively broken up and a more uniform absorption solution is produced.

In Fig. 4 I have shown a further modification in which a helical member 42 is disposed within conduit 35. The helical member 42 is twisted and formed of a number of strands or smaller wires which are preferably helically wound in opposite directions. By employing a twisted wire of this character small gaps are formed at the inner wall of conduit 35 to permit flow of liquid through the lower parts of the dams formed between the indentations 36.

The provision of a helical member of the character shown in Figs. 2 to 4 inclusive increases the liquid surface contact considerably. When liquid passes over the barriers formed by the indentations 36, the liquid tends to run up along the helical members at the dams formed by these members. Since the flow of liquid is effectively throttled at the dams, liquid tends to accumulate

at these regions and is subsequently drawn downward into the narrow gaps or spaces beneath the dams to produce a relatively strong eddy effect.

In making the improved absorber just described, the helical members or coils may be formed to the desired shape and inserted into the conduits. The indentations 36 may then be made in conduits 35 and the cooling fins 19 thereafter secured in place. If desired, the helical coils may be screwed into the conduits after the indentations 36 have been formed. The pitch of the helical members may be made 1, 2, or 3 times the distance between two indentations 36 and the helical members screwed into position in such a manner that the wires will not strike the indentations 36.

In view of the foregoing, it will be understood that I have provided an improvement to increase the surface contact between a gas and a liquid which may be used in the evaporator or cooling element 10 as well as the absorber 18. While I have shown and described several embodiments of my invention, such variations and modifications are contemplated as fall within the true spirit and scope of my invention.

What is claimed is:

1. Absorption refrigeration apparatus having a circuit for circulation of a gas and including a conduit having an inlet and outlet at different elevations, a member for introducing liquid in said conduit for downward flow therein in the presence of said gas, a helical wire disposed within said conduit and arranged to contact the inner wall thereof irregularly to provide spaces between the lower parts of successive turns and the inner wall of said conduit, the lower parts of said wire serving as dams and said spaces permitting flow of liquid below said dams, and barriers in said conduit at spaced intervals between said dams to form a series of pools in the path of flow of liquid.

2. Absorption refrigeration apparatus having a circuit for circulation of a gas and including a conduit having an inlet and an outlet at different elevations, a member for introducing liquid in said conduit for downward flow therein in the presence of said gas, and a helical strip arranged within said conduit and having notches or openings at spaced intervals, the lower parts of successive turns of said helical strip serving as dams in the path of flow of liquid and said notches or openings permitting the flow of liquid at the lower parts of said dams.

3. Absorption refrigeration apparatus having a circuit for circulation of a gas and including a conduit having an inlet and an outlet at different elevations, a member for introducing liquid in said conduit for downward flow therein in the presence of said gas, and a helical strip within said conduit and having one longitudinal edge thereof bearing against the inner wall of said conduit, said strip extending inwardly from the inner wall of said conduit, and said strip having notches along the longitudinal edge bearing against the inner wall of said conduit.

4. Absorption refrigeration apparatus having a circuit for circulation of a gas and including a conduit having an inlet and an outlet at different elevations, a member for introducing liquid in said conduit for downward flow therein in the presence of said gas, and a helical wire extending axially within said conduit and contacting the inner wall thereof whereby the lower portions of said wire provide dams for liquid at spaced intervals, said wire comprising a plurality of

closely woven twisted smaller wires whereby a plurality of small gaps are formed at said dams to permit flow of liquid therethrough.

5. Absorption refrigeration apparatus having a circuit for circulation of gas and including a conduit having an inlet and outlet at different elevations, a member for introducing liquid in said conduit for downward flow therein in the presence of said gas, said conduit having indentations at spaced intervals to provide barriers over which liquid must flow, and means disposed between said indentations to provide dams having openings in the lower parts thereof.

6. Absorption refrigeration apparatus having a circuit for circulation of a gas including a conduit having an inlet and an outlet at different elevations, means for introducing liquid in said conduit for downward flow through said conduit in the presence of said gas, said conduit having barriers at spaced intervals to form a series of pools in the path of flow of liquid, and a fixed member in said conduit having parts disposed between said barriers in a manner to project into said pools to cause turbulence in flow of liquid in said pools, said parts being connected by other parts disposed above said pool forming barriers.

7. In refrigeration apparatus including a generator, a condenser, an evaporator, an absorber, and members connecting the aforementioned parts to form a complete system for circulation of a refrigerant and absorption liquid, and an inert gas, said absorber including a conduit arranged for gravity flow of absorption liquid

therein, barriers at spaced intervals in said conduit to form pools in the path of flow of liquid therein, and means within said conduit having fixed parts located between said barriers in a manner to project into said pools to create turbulence in flow of liquid in said pools, said parts being connected by other parts located above said barriers.

8. Absorption refrigeration apparatus having a circuit for circulation of inert gas and including a part arranged for gravity flow of liquid therethrough, means to introduce liquid in said part for gravity flow therein in the presence of said gas, said part having barriers at spaced intervals in the path of flow of liquid to form a plurality of pools and means including a member extending over said barriers and having fixed parts projecting downward between said barriers into said pools to produce an eddy effect in liquid flowing in said pools.

9. Absorption refrigeration apparatus having a circuit for inert gas including a part arranged for gravity flow of liquid therethrough, a means to introduce liquid in said part for gravity flow therein in the presence of said gas, said part having inward projections forming barriers at spaced intervals in the path of flow of liquid to form a series of pools, and means in said part shaped to extend upward over said barriers and downward between said barriers so as to project into said pools and create turbulence of liquid flowing in said pools.

ALVAR LENNING.
